[57] CLAIM

The ornamental design for a combined keyboard and electronic learning aid, as shown and described.

DESCRIPTION

FIG. 1 is a top plan view of a combined keyboard and electronic learning aid showing our new design;
FIG. 2 is a left side elevational view thereof;
FIG. 3 is a right side elevational view thereof;
FIG. 4 is a rear elevational view thereof;
FIG. 5 is a front elevational view thereof;
FIG. 6 is a bottom plan view thereof;
FIG. 7 is a top plan view thereof, with the keyboard portion removed for clarity of illustration only.
FIG. 8 is a left side elevational view thereof;
FIG. 9 is a right side elevational view thereof;
FIG. 10 is a rear elevational view thereof;
FIG. 11 is a front elevational view thereof;
FIG. 12 is a bottom plan view thereof;
FIG. 13 is a top plan view of the keyboard portion of FIG. 1 shown separately for clarity of illustration only.
FIG. 14 is a left side elevational view thereof;
FIG. 15 is a right side elevational view thereof;
FIG. 16 is a rear elevational view thereof;
FIG. 17 is a front elevational view thereof;
FIG. 18 is a bottom plan view thereof; and
FIG. 19 is an enlarged top perspective view of FIG. 1.
